UNITED STATES PATENT OFFICE.

KENNETH DAVIS, OF ST. BENEDICT, PENNSYLVANIA, ASSIGNOR TO REMBRANDT PEALE, OF NEW YORK, N. Y.

PUMP.

Application filed August 23, 1920. Serial No. 405,324.

To all whom it may concern:

Be it known that I, KENNETH DAVIS, a citizen of the United States, residing at St. Benedict, in the county of Cambria and 5 State of Pennsylvania, have made certain new and useful Improvements in Pumps, of which the following is a specification.

The invention relates to pumps, and more especially to the driving mechanism and 10 valve mechanism thereof.

Objects and advantages of the invention will be set forth in part hereinafter and in part will be obvious herefrom, or may be learned by practice with the invention, the 15 same being realized and attained by means of the instrumentalities and combinations pointed out in the appended claims.

The invention consists in the novel parts, constructions, arrangements, combinations 20 and improvements herein shown and described.

The accompanying drawings, referred to herein and constituting a part hereof, illustrate one embodiment of the invention, and 25 together with the description, serve to explain the principles of the invention.

Of the drawings:—

Fig. 1 is a side elevation of a pumping mechanism embodying the invention, and 30 showing one of the pump cylinders in vertical section;

Fig. 2 is an end elevation, looking at Fig. 1 from the right;

Fig. 3 is in part a top plan and in part a 35 horizontal section taken on the line 3—3 of Fig. 1;

Fig. 4 is a detail of the piston driving wheel or disc;

Fig. 5 is a fragmentary sectional detail 40 taken on the line 5—5 of Fig. 3;

Fig. 6 is an end elevation, corresponding to Fig. 2, but showing another form of valve mechanism;

Fig. 7 is a fragmentary top plan, corresponding to Fig. 6, but showing the pump cylinders in horizontal section;

Fig. 8 is a fragmentary, enlarged horizontal section of the valve mechanism on line 8—8 of Fig. 9; and

Fig. 9 is a diagrammatic elevation, showing 50 the two pump cylinders opened out from each other angularly, and the valves also diagrammatically, the view being made in this manner for the sake of greater clearness in the showing.

Referring now in detail to the embodiment of the invention illustrated by way of example in the accompanying drawings, a reciprocating pump is shown driven by a rotary motor through rotary connections, embodying speed reducing gearing, and preferably an electrical motor is employed.

In such embodied form, an electrical motor 1 is shown, having a speed reducing gearing mounted on the shaft 2 thereof. As 65 embodied, the speed reducing gearing comprises an eccentric 3, mounted on the shaft 2, and fixed to rotate therewith by a key 4. Mounted loosely upon the eccentric 3 is a cylindrical bushing 5, and mounted loosely 70 on the bushing 5 is a geared pinion 6, a shoulder 7 on the eccentric serving to hold the pinion and sleeve against longitudinal displacement. The geared pinion 6 is in mesh with an internally geared ring 8, 75 which ring is supported in a part 10 of the machine frame and is held from rotation by suitable means, such as keys 9.

Loosely mounted on the sleeve 5 is a 80 geared pinion 13, with its side face in engagement with the pinion 6, the two pinions being fastened together by suitable means, such as rivets or pins 14, so that they will rotate together.

Mounted on the machine frame (Fig. 3) 85 is a stub shaft 15 held in position in its bearing 16 by a nut 17, screw threaded upon the back end of the shaft. Sleeved on the shaft 15 is a bushing 18, and journaled on the bushing 18 is a rotary piston actuating member 19, which in the present embodiment is 90 in the form of a sinuous wheel or disc.

To drive the piston actuating member 19, there is provided, extending outwardly from said member a cylindrical portion 20, provided at its outer end with an internal gear ring 21, with which gear ring meshes the geared pinion 13 already described. The disc 19 and its shaft 16 in this construction are in alignment and concentric with the 100 motor shaft 2.

The operation of the hereinbefore described gearing for imparting rotary motion at greatly reduced speed to the disc 19 from the motor shaft 2, is substantially as 105 follows:—

By reason of the eccentric mounting of the geared pinion 6 upon the shaft 2, it passes circumferentially about and comes 110 consecutively into engagement with the in-

ternal gear teeth of the ring 8. The ring 8, it will be recalled, is in fixed non-rotating position on the frame, and as a result the pinion 6 will have a backward movement of rotation about its own axis relatively to the rotation of motor shaft 2 equal to the distance of the difference of the number of teeth between the pinion 6 and the gear ring 8 for each rotation of the shaft 2. The pinion 13, being fixed to the pinion 6 will rotate therewith, and pass circumferentially about the internal gear 21, and its teeth will mesh consecutively with the geared teeth of the internal gear ring 21, which is fixed to the piston driving disc 19. This will impart rotary motion to the disc 19 in an opposite direction equal in distance to the difference in the number of teeth on the pinion 13 and the internal gear ring 21. Thus it will be seen that a greatly reduced rotary movement is imparted to the disc 19 through the double gear reduction as described.

As embodied, the pump is shown having two double acting cylinders 26 and 27, provided, respectively, with reciprocating pistons 28 and 29, having piston rods 30 and 31. As embodied, the piston rods are driven from the rotary member 19, and preferably by direct engagement with the edge thereof, thereby making a very simple mechanism.

The embodied connections for each piston rod to the driving means comprises a head 32 recessed to permit the edge of the member 19 to project thereinto. The edge of the disc 19 is preferably formed perpendicular to its axis to provide an easy running bearing for the piston rod connections. Each of the heads 32 is provided with a pair of friction rollers 33 and 34, which rollers bear against the opposite sides of the disc 19. The heads 32 serve also as guides for the piston rods, running on guideways 36 formed on the machine frame. The piston rods may be provided with packing glands 35 of any suitable or approved form.

In Figs. 1, 2 and 3 of the drawings, the cylinders are shown provided with an ordinary form of check valves both for the intake and for the discharge. An intake or suction pipe 39 branches into pipes 40 and 41; pipe 40 branches into two pipes 42 and 43, provided, respectively, with check valves 46 and 47; and pipe 41 branches into two pipes 44 and 45, provided with similar check valves (not shown). The lift or outlets from cylinder 27 is through pipes 48 and 49 which converge into a pipe 50. The outlets from cylinder 28 is through pipes 51 and 52, which converge into a pipe 53. Pipes 50 and 53 converge into a pipe 54, constituting a common lift or outlet pipe for the two cylinders. Pipes 48 and 49

are provided, respectively, with check valves 55 and 56, and pipes 51 and 52 are likewise provided with check valves (not shown).

In Figs. 6 to 9, a form of valve mechanism is shown which is dirt proof and positively acting, whereby fragments of solid material which may be sucked up through the pump intake are promptly expelled from the valves and do not destroy or impair the pumping action. This is very necessary in many kinds of work, as for instance, in mine work, wherein water is pumped containing particles of coal or rock, and pumps are run for long periods without supervision. With the ordinary forms of valves, a particle of coal or rock lodging beneath a valve may destroy the efficiency of the pump, or terminate the pumping action while the pump continues to run, until discovered and removed by an attendant.

In connection therewith means are preferably provided embodying a common valve mechanism for a plurality of pump cylinders, although a separate valve mechanism may be provided for each cylinder, if desired.

Referring now in detail to Figs. 6 to 9, they show a dirt proof valve system common to the two pump cylinders, and common also to the suction or intake and to the lift or outlets from the two cylinders.

Referring first to the intake system, a common suction or intake pipe 60 for all the intake ports of the two cylinders is provided, opening into a common valve chamber 61. From this chamber 61 pipes lead to the suction or inlet ports at each end of each of the pump cylinders 26 and 27. Of these, pipes 62 and 63 lead, respectively, from the valve chamber to the inlet ports 64 and 65, at the two ends, respectively, of cylinder 26, and pipes 66 and 67 lead from the valve chamber to the inlet ports 68 and 69, at the two ends, respectively, of cylinder 26. Pipes 62 and 67 open, respectively, out of ports 70 and 71 in the valve chamber 61, and the ports 70 and 71 are located diametrically opposite to each other in the valve chamber. Pipes 63 and 66 open, respectively, out of another pair of inlet ports 72 and 73 in the valve chamber 61, which are likewise located diametrically opposite to each other. This mechanism provides for the intake of the two double-acting cylinders.

A single valve, preferably a rotary valve, controls the four ports 70 and 71, and 72 and 73 (thereby controlling the intake at each end of each cylinder), the valve chamber 61 being correspondingly preferably cylindrical.

Referring now to the lift or outlet system, a valve chamber 77 is provided, also cylindrical, and preferably structurally unitary with valve chamber 61, the two chambers

being separated by a partition or head 78. The two valve chambers are in a common casing 93, and the two valves are preferably mounted upon and actuated by a common 5 shaft, as will be later described. A common lift or outlet pipe 79 from the valve chamber 77 is likewise preferably provided.

From valve chamber 77, pipes lead to the outlet ports at each end of the cylinders 26 10 and 27, the arrangement being preferably the same as for the inlet system. In detail, pipes 80 and 81 communicate from valve chamber 77 to the outlet ports 82 and 83, at the opposite ends, respectively, of the cylinders 26 and 27. The pipes 80 and 81 open 15 into the valve chamber 77 by ports 84 and 85, respectively, which are positioned diametrically opposite each other in the walls of the valve chamber.

20 The two other cylinder outlet pipes 86 and 87 communicate also from the valve chamber 77 with the outlet ports 89 and 90, respectively, in the two cylinders 26 and 27. The pipes 86 and 87 open into the valve 25 chamber 77 by ports 91 and 92, respectively, which are located diametrically opposite each other in the valve chamber.

A convenient arrangement in plan of the pipes leading into and out of the valve 30 chamber or casing 93, the upper part thereof forming the valve chamber 77 and the lower part thereof forming valve chamber 61, is shown in Fig. 8.

The valves are all the same or similar in 35 construction and operation, and a single description will suffice. A valve 95 is mounted on a shaft 96 for rotary motion within the cylindrical valve casing 93, the shaft 96 being journaled in the heads 97 and 98 of 40 the casing 93.

Valve 95 is provided with a body portion 45 99 surrounding the shaft 96, and with two projecting heads 100 and 101, which have arcuate or cylindrically curved ends or faces 102 and 103, adapted to fit closely against and to rotate within the valve cylinder walls, these heads serving to open and to close the ports in the valve chamber walls. The heads 100 and 101 are provided with more or less 50 sharp edges in the parts or ends thereof extending longitudinally of the cylinder, the heads being undercut on their inward faces extending toward the center of the valve cylinder. These edges assist in preventing the lodgment of dirt in the valves.

A brief description of the operation of one of the valves, in connection with Figs. 8 and 9, will suffice for both. The face 102 in its two positions serves alternately to 55 close and to open the outlet ports (or inlet ports, as the case may be) for the opposite ends of either one of the cylinders 26 or 27. The other face 103 in its two positions serves alternately to close and to open the outlet 60 ports (or inlet ports, as the case may be) for

the other of the two cylinders 26 or 27. Thus the valve 95, and considering the intake system for example, by its rotation and pauses or dwells, will open the intake at the front end of cylinder 26 and the intake at 70 the rear end of cylinder 27, and will close the intake at the rear end of cylinder 26 and the intake at the front end of cylinder 27.

On reversing the position of the valve, the 75 reverse conditions obtain as to the opening and closing of the inlet ports. As the pump pistons are moving in opposite directions, the valve operation just described corresponds to the water flow created by the 80 pistons, the water discharging from the opposite ends of the two cylinders on any particular stroke, and changing ends with the reversal of the piston stroke. It will also be understood that when an inlet port at 85 one end of a cylinder is open, the outlet port at that end of the cylinder is closed, these conditions being essential to pump operation and elaborated description there- 90 of is deemed unnecessary.

The foregoing description will fit equally the outlet valve system and will be understood as applying thereto without repetition. The showing of the valves in Fig. 9 is purely diagrammatic, the actual mechanism being shown in Fig. 8, the four outlet pipes preferably entering the valve chamber in one horizontal plane in valve chamber 77, and the four inlet pipes being similarly arranged in valve chamber 61. The position 95 of all the ports and valves is best shown simultaneously, however, by the diagrammatic arrangement of Fig. 9.

In the embodied form, the valves are positively actuated, and this is preferably effected by rotary mechanism operated from the motor. In such embodied form, the shaft 15 extends from bearing 16 on the opposite side from the piston driving disc 19.

Fixed on shaft 15 is a cylindrical cam 108 having an operating groove 109 formed therein. Working in groove 109 is a cam roller 110, which is mounted on a crank arm 111, which arm is fixed to the valve shaft 96, already described.

The cam groove 109 is shaped to give the required and properly timed movements and dwells of the valves 95, as indicated by Figs. 8 and 9. The valve movement provided is quick and simple, having little mechanism (two valves serving for the eight ports of the two cylinders), and is positively driven from the driving shaft for the pump pistons. The valves are dirt proof, as particles of coal or rock lodging in any of the valve ports will be dislodged at once by the swinging, sharp edges of the heads 100 and 101. The valve cylinder heads 97 and 98 can be removed to clean the valve chambers.

The invention in its broader aspects is 130

not limited to the specific mechanisms shown and described but departures may be made therefrom within the scope of the accompanying claims without departing from the principles of the invention and without sacrificing its chief advantages.

What I claim is:—

1. A pump including in combination a rotary motor, gearing on the motor shaft, a fixed internal gear meshing therewith, a sinuous rotary member having an internal gear likewise meshing with the gearing on the motor shaft, a pump cylinder having a piston and a piston rod having a head engaging the rim of the sinuous rotary member to reciprocate the piston.

2. A pump including in combination a rotary motor, gearing eccentrically mounted on the motor shaft, a fixed internal gear meshing therewith, a sinuous rotary member having an internal gear likewise meshing with the gearing on the motor shaft, a pump cylinder having a piston and a piston rod having a head engaging the rim of the sinuous rotary member to reciprocate the piston.

3. A pump including in combination a rotary motor, an eccentric fixed to the motor shaft, gearing loosely mounted on the eccentric, a fixed internal gear meshing therewith, a sinuous rotary member having an internal gear likewise meshing with the gearing on the motor shaft, a pump cylinder having a piston and a piston rod having a head engaging the rim of the sinuous rotary member to reciprocate the piston.

4. A pump including in combination a rotary motor, gearing on the motor shaft, a fixed internal gear meshing therewith, a rotary member having an internal gear meshing therewith, a pump cylinder having a piston and piston rod and connections for reciprocating the piston rod from the geared rotary member.

45 5. A pump including in combination a rotary motor, gearing eccentrically mounted on the motor shaft, a fixed internal gear meshing therewith, a rotary member having an internal gear meshing therewith, a pump cylinder having a piston and piston rod and connections for reciprocating the piston rod from the geared rotary member.

55 6. A pump including in combination a rotary motor, gearing on the motor shaft, a fixed internal gear meshing therewith, a rotary member having an internal gear likewise meshing with the gearing on the motor shaft, a pump cylinder having a piston and piston rod operated from said rotary member and valve gearing operated by said rotary geared member.

65 7. A pump including in combination a rotary motor, gearing on the motor shaft, a fixed internal gear meshing therewith, a rotary member concentric with the motor

and having an internal gear likewise meshing with the gearing on the motor shaft, a pump cylinder having a piston and piston rod operated from said rotary member and valve gearing operated by said rotary geared member.

8. A pump including in combination a rotary motor, gearing on the motor shaft, a fixed internal gear meshing therewith, a rotary member having an internal gear likewise meshing with the gearing on the motor shaft, a pump cylinder having a piston and piston rod operated from said rotary member, a second rotary member rotating with said geared rotary member and valve gearing operated thereby.

9. A pump including in combination a rotary motor, gearing on the motor shaft, a fixed internal gear meshing therewith, a rotary member concentric with the motor and having an internal gear likewise meshing with the gearing on the motor shaft, a pump cylinder having a piston and piston rod operated from said rotary member, a second rotary member concentric and rotating with said geared rotary member and valve gearing operated thereby.

10. A pump including in combination a rotary motor, gearing on the motor shaft, reduction gearing in mesh therewith including a rotary member both of the said gears bearing rotatable on parallel axes, a cylinder having a piston and piston rod driven from said rotary member, and valve gearing including a rotating cam also driven from said rotary member.

11. A pump including in combination a rotary motor, gearing on the motor shaft, reduction gearing in mesh therewith including a rotary member concentric with the motor shaft, a cylinder having a piston and piston rod driven from said rotary member, and an oscillating valve also driven from said rotary member.

110 12. A pump including in combination a rotary motor, gearing on the motor shaft, reduction gearing in mesh therewith including a rotary member concentric with the motor shaft, a cylinder having a piston and piston rod driven from said rotary member, a second concentric rotary member and valve gearing driven thereby.

120 13. A pump including in combination a rotary driving shaft, cylinders parallel to the shaft, double-acting pistons in the cylinders, means operatively connecting the pistons to said shaft, valve means, and a cam rotatable with said shaft for operating the valve means.

125 14. A pump including in combination a rotary driving shaft, a cylinder parallel thereto, a double acting piston in the cylinder, means operatively connecting the piston and the driving shaft, an oscillating valve, and a cam, mounted on the driving

shaft and rotatable therewith, for operating the oscillating valve.

15. A pump comprising in combination a rotary driving shaft, a plurality of cylinders parallel thereto, double-acting pistons in the cylinders, an oscillating valve shaft, inlet and outlet controlling valves mounted on the oscillating shaft, and means for driving the pistons and the valve shaft from the driving shaft.

16. A pump including in combination a rotary driving shaft, a rotary member, double reduction gearing cooperating with the driving shaft and with the rotary member, the axes of the elements of the said gearing being substantially parallel to said driving shaft, and a pump piston driven by said rotary member.

17. A pump including in combination a rotary driving shaft, a rotary member, double reduction gearing cooperating with the driving shaft and with the rotary member, the axes of the elements of the said gearing being substantially parallel to said driving shaft, a pump piston driven by said rotary member, and valve gearing driven by said rotary member.

18. A pump including in combination a rotary driving shaft, a rotary member, double reduction gearing cooperating with the driving shaft and with the rotary member, the axes of the elements of the said gearing being substantially parallel to said

driving shaft, a plurality of double-acting pistons actuated by the rotary member, and valve gearing cooperating with the several pistons and driven from said rotary member.

19. A pump comprising in combination a plurality of parallel cylinders, a double acting piston in each cylinder, an electric driving motor having its shaft parallel to the axes of the cylinders, means including reduction gearing, operatively connecting the motor shaft to the several pistons, and valve means also driven through said reduction gearing operatively connected to both ends of the several cylinders.

20. A pump comprising in combination a plurality of parallel cylinders, a double-acting piston in each cylinder, an electric driving motor having its shaft parallel to the axes of the cylinders and equidistant therefrom, means, including reduction gearing, operatively connecting the motor shaft to the several pistons, and oscillating valve means also driven through said reduction gearing operatively connected to both ends of the several cylinders.

In testimony whereof, I have signed my name to this specification, in the presence of two subscribing witnesses.

KENNETH DAVIS.
